[57] CLAIM

The ornamental design for an extending attachment for

torque-applying hand tools or the like, as shown and described.

DESCRIPTION

FIG. 1 is a perspective view of an extending attachment for torque-applying hand tools or the like showing a first embodiment of my new design;

FIG. 2 is an enlarged top plan view thereof;

FIG. 3 is an enlarged side elevational view thereof, the opposite side being a mirror image;

FIG. 4 is an enlarged bottom plan view thereof;

FIG. 5 is an enlarged front elevational view thereof, the rear view being identical;

FIG. 6 is an enlarged perspective view thereof showing the variable-size top insert, for facilitating use with "channel-lock" pliers, in broken lines for illustrative purposes only;

FIG. 7 is a perspective view of an extending attachment for torque-applying hand tools or the like showing a second embodiment of my new design;

FIG. 8 is an enlarged top plan view thereof;

FIG. 9 is an enlarged side elevational view thereof, the opposite side being identical;

FIG. 10 is an enlarged bottom plan view thereof;

FIG. 11 is an enlarged front elevational view thereof, the rear view being identical; and

FIG. 12 is an enlarged perspective view thereof showing the variable-size top insert for facilitating use with "channel-lock" pliers in broken lines for illustrative purposes only.

The wrenches and top insert in FIGS. 1 and 6 are shown in broken lines for illustrative purposes only and form no part of the claimed design.
